UNITED STATES PATENT OFFICE.

EMIL ROHNER, OF RHEINECK, SWITZERLAND, AND EDOUARD SIMIC, OF VIENNA,
AUSTRIA.

ELECTRIC INCANDESCENT LAMP.

Application filed December 14, 1921. Serial No. 522,451.

To all whom it may concern:

Be it known that we, EMIL ROHNER, a citizen of the Republic of Switzerland, and EDOUARD SIMIC, a subject of the King of 5 Servia, and residents, respectively, of Rheineck, in the Canton of St. Gall, Switzerland, and of Vienna, in the Republic of Austria, have invented certain new and useful Improvements in Electric Incandescent 10 Lamps, of which the following is a specification.

The electric incandescent lamps hitherto known most of all have the drawback that as soon as the single filament has been burnt 15 out or broken they become completely valueless and have consequently to be replaced.

Now, it is the object of the present invention to overcome such drawback, the characteristic feature of our invention consisting in that provision is made of a second and independent incandescent filament which, by the aid of a third contact, is adapted to be mounted in the known electric lamps irrespective of their form, size or power. Thus, 25 if and when the ordinary filament has been burnt out or broken, the second filament is brought into the electric circuit by means of the said third contact so that the great advantage is gained that the lamp, even though 30 the first filament has been rendered useless, may be further employed.

In order that the invention may be clearly understood reference is made to the accompanying drawings, in which:

Fig. 1 shows an elevation, partly in section, of a first construction and arrangement of our improved electric incandescent lamp, and

Fig. 2 shows a similar view of a modification.

Similar parts are designated by like references throughout the views and the specification.

In ordinary electric incandescent lamps of 45 the form, for instance, illustrated in Fig. 1, the lamp body or glass-bulb *a* has centrally mounted therein a filament support *b* of glass which, like the bulb, is of the well known construction and provided at the top 50 and near the bottom with a collar *b'* and *b''* respectively. These collars serve for the attachment therein, in star form, of a series of wires *c* having hooks at their outer ends to which the filament is secured in the usual

manner, that is, by attaching one end of the 55 filament to one of the two electric contacts commonly provided and guiding it zigzag-wise up and down and over the said hooks in order finally to attach the other end of the filament to the second contact.

As already indicated our invention does not interfere with the construction and arrangement of ordinary electric incandescent lamps except that the collars *b'* and *b''* are 60 preferably made of a larger size to permit 65 the mounting therein of a second series of wires *d*. These wires *d* are also disposed in star form but made rather longer than those designated by *c*. A second filament, indicated in dotted lines in Fig. 1, is similarly 70 secured upon the hooked ends of the wires *d* as that described with reference to the wires *c* and has one of its contacts common with the first filament, the other end, however, being connected to a third contact mounted 75 in the lamp and severely insulated from and in respect of the aforesaid second contact. There is thus a double winding of filament, 80 namely an inner and an outer winding.

The arrangement of the three contacts is 80 the following:

Two of the three contacts remain of the disposition known in electric lamps of the type commonly used, the positive contact 1 being located in the screw-threaded sleeve *e* 85 by means of which the lamp is mounted, and the negative and insulated contact 2 being located in the negative pole-carrying fitting *g* of the electric lamp. The third contact 3, connecting with a contact member *h* and the outer filament, is fitted close to the said second contact but is insulated therefrom by means of a strip *i* of insulating material, 90 both the contact member *h* and the strip *i* being mounted in a recess provided in the 95 aforementioned fitting *g*.

It will thus be seen that, whereas in the ordinary electric lamps the insulation of the usual two contacts is effected by means of a glass cap or the like carrying a metal 100 strip to connect it with the negative pole, the two poles, that is, the two positive or negative poles according to this invention are mounted on the glass insulation and separated from one another by the insulating strip *i*, the latter as shown in Fig. 1 however causing the insulation of the contact 2 only.

Assuming now that the inner filament has been rendered useless, the insulating strip *i* is withdrawn from its recess in the fitting *g* in order to bring into action the third and hitherto insulated contact 3 with contact member *h*, and consequently cause the lighting of the outer filament. Supposing, on the other hand, the electric lamp from the beginning to be fitted without the insulating device described, both filaments are simultaneously lighted. In such case and since the filaments are parallelly mounted, the intensity of the electric current must necessarily be doubled.

This invention applies equally well to electric incandescent lamps of other shape, such as to a lamp of the kind illustrated in the modification, Fig. 2, in which the filament *p* is of undulatory form and mounted on the filament support *b* by means of a series of wires *c* secured at the circumference of the collar *b'* of said support. In this case, too, we make provision of a second filament *q* which is arranged parallel to the first filament and suspended from the collar *b'* by means of another series of wires *c'*. The arrangement of the three contacts 1, 2, 3, and that of the insulating strip *i* and contact member *h* is substantially the same as

hereinbefore described with reference to Fig. 1.

What we claim as novel and desire to secure by Letters Patent is:—

In the herein-described electric incandescent lamp of the kind having two filaments mounted therein, the combination, with a screw-threaded metal sleeve carrying the lamp and a lamp-socket attached to the sleeve and provided with a recess, of a common contact located in the said sleeve and connecting with one end of each of the filaments, two other and separate contacts fitted at the face of the socket, and a switch detachably mounted in the aforesaid recess and comprising a contact member and an insulating member adapted to cover one or the other of the separate two contacts.

In testimony whereof we have hereunto set our hands in the presence of the subscribing witnesses.
